UNITED STATES PATENT OFFICE.

JOSHUA F. AMES, OF ROCKLAND, MASSACHUSETTS.

STITCHING-JACK FOR BOOTS OR SHOES.

SPECIFICATION forming part of Letters Patent No. 291,661, dated January 8, 1884.

Application filed November 12, 1883. (No model.)

To all whom it may concern:

Be it known that I, JOSHUA F. AMES, of Rockland, county of Plymouth, State of Massachusetts, have invented an Improvement in Boot and Shoe Stitching Jack, of which the following description, in connection with the accompanying drawings, is a specification, like letters on the drawings representing like parts.

This invention has for its object the production of a novel stitching-jack to hold boots and shoes while attaching the sole to a welt or to a welt-sole by hand.

My improved stitching-jack is composed of a rotating head, having a heel and toe rest, preferably made adjustable with relation to each other and also as to their length, to adapt the same to shoes of different lengths and to lasts of different shapes. Co-operating with said head which holds the last and shoe is a sole-presser, which rests in the channel near the stitching-point, the supports for the said head and the sole-presser being forced toward each other in such manner as to cause the last and sole-presser to act as a clamp to force the sole and welt together closely near the stitching-point and hold them together firmly while the stitch is being made, thus preventing the sole from sliding or moving on or with relation to the welt, as is apt to be the case when a shoe-maker, making a welted shoe by hand, is making holes through the welt and sole by a hand-operated awl.

When a shoe-maker soles a welted boot or shoe, as usual, by hand, he places the thumb of his left hand against the sole near its edge, to thus form a support for the sole near that point from which the point of the awl, held in the right hand of the operator, is to emerge after having been passed through the welt. In this hand method the pressure of the thumb is insufficient to hold the sole with sufficient firmness while the awl is being forced through the welt and sole, to prevent the welt and sole from springing or bending unequally. Unequal bending of the welt and sole as the awl is being forced through them causes the inner face of the outer sole to slip upon the inner face of the welt or welt-sole, which results in the formation of holes in the sole, which are not at right angles to the face of the welt or the face of the outer sole; and the sole and welt,

when such holes are filled in with thread and drawn taut, fail to draw the sole and welt together properly; and, as the shoe is used in walking, the sole will move on the welt, owing to imperfect joining, and the movement of the sole will soon act to cut off the stitches holding it to the welt.

Figure 1 represents in front end view a stitching-jack embodying my invention, the hand wheel or plate against which the arm m^4 bears during its movement being broken out to show the said arm back of it, the frame part of the machine being also broken apart, and the lower part thereof containing the treadles being carried forward to save space upon the drawing; and Fig. 2 is a section of Fig. 1 on the dotted lines $x x$, the sole-presser cut off at the right of such section-line being, however, shown in dotted lines.

The frame-work A has a suitable bearing, a , for the spindle b , flattened at its end to enter a recess, 40, made in the curved base 21 of the cross-bar b^2 of the head, the said spindle and the curved base of the bar b^2 being connected by the part b' , and the spindle being surrounded by a spiral spring, b^4 , and a nut, b^5 . The spring b^4 permits the spindle to be moved longitudinally. The outer end of the spindle b is acted upon by the toe c^2 of a lever, c , pivoted at c' , the said lever having its long end attached by link c^3 to a pivoted treadle, c^4 , the rear end of which is acted upon by a projection from one side of the pivoted lever c^5 , having the foot-piece c^6 . The cross-bar b^2 has adjustably pivoted upon it at b^3 the heel-rest d , having, as herein shown, a heel-pin, d^2 , which is made to enter the last d^3 . The heel-rest d is made adjustable by the pivoted screw d^4 and nut d^5 . The toe-rest e is made adjustable in the direction of its length by the screw e' in the part e^2 , the latter in turn being adjustably connected by screw e^4 to the cross-bar b^2 . The entire head holding the last and shoe may be vibrated about the pivot b' , and the head and spindle may be rotated.

The drawings show the upper f , inner sole, g , welt w , and outer sole, h , provided with the channel h^2 . In Fig. 1, part of the outer sole is broken away to show the welt under it. The sole-presser m , composed of a rod having at its end a lip, m' , to enter the channel h^2 , is

adjustably attached to the socket m^2 by screw m^3 , and the socket is pivoted on the arm m^4 , the hub 14 of which is placed loosely on the hub of the hand wheel or plate 10, so that the 5 said arm may be turned by the operator about the said hub as a center when it is desired to raise and lower the sole-presser or change its position to adapt it to the changing position of the channel as the shoe is moved to be 10 stitched, the lip of the presser entering the channel h^2 near the point where the awl is to emerge from it, and preferably from one to twelve stitches distant. The hub 14 is splined to slide on the slide-rod n . The arm m^4 is re- 15 tained on the sleeve of the hand-wheel by the collar 16. The slide-rod n , supported in bearings n^1 n^2 , suspended from the plate n^3 , and splined, as at 6, so as to slide but not rotate in its bearings, is provided with an 20 adjustable nut and a spring, n^5 , which latter acts to hold the sole-presser m against the sole when the awl is being forced through the welt and sole, or, as the awl-holes, if previously made by a machine such as described 25 in United States Letters Patent No. 191,387, are being opened, by an awl for the reception of the waxed thread. The force by which the sole-presser is held against the sole is measured by the strength of the spring n^5 , and 30 may be adjusted by the nut n^4 . This slide-rod is provided with a series of notches, 13, one of which is entered by a latch, 12, pivoted at 17, on the hand-wheel. Changing the latch from one to another notch 13 enables 35 the hand-wheel and sole-presser to be placed nearer to or farther from the end of the slide-rod, according to the requirements of the last and shoe thereon. A boot or shoe having been applied to the head, as in the drawings, 40 the operator will press upon the foot part o of the treadle o' , so that its shorter arm will rise and act against the rear end of the lever o^2 , depressing its front end, which is joined with the rod o^3 , attached to the elbow-lever o^4 , piv- 45 oted at o^5 , and having its opposite end resting against the slide-rod n . Depression of the lever or treadle o' will cause the slide-rod to be moved to the left, Fig. 2, carrying the sole-presser m with it away from the sole, and com- 50 pressing the spring n^5 . This done the operator will engage the sole-presser and raise or lower it to place the lip m^4 thereof at the proper height to enter the channel a short distance from that part of the sole where the awl 55 is next to be driven through the welt and sole. The head c , which holds the boot or shoe, the said head being composed of the parts e e^2 b^2 d d^2 , is pivoted at b' on the end of a rod, b , held in the bearing a . The rod b is surrounded 60 by the spring b^4 , backed up by a nut, b^5 . The spring b^4 acts to draw the curved base 21 of the bar b^2 into a slot made in the face of the socket-piece 22, interposed between the said curved base 21 and the upright A^2 . The curved base 65 of the bar b^2 may be turned in the slot of the said socket-piece about the pivot b' when it is desired to move the boot or shoe in the direc-

tion of the length of the sole; but before this is done the rod must be pushed to the left, viewing Fig. 2, far enough to remove the curved base 21 from its seat in the socket-piece 22. This may be done by means of the elbow-lever c , pivoted at c' , and joined by rod c^3 with a treadle, c^4 , the rear end of which is elevated by a projection from the rear end of the lever c^5 , having a foot-pad, c^6 . While the rod b is pushed forward by the lever c , the latter is removed from its engagement with a notch of the nut b^5 , at which time the entire head may be rotated, if desired, the rod b turning in the bearing a . The nut b^5 fits the rod b closely, and the lever c , pressed up by the spring 24, engages one of a series of notches in the nut, and locks the same and the rod. To prevent the waxed end 25 from being caught under the 80 wheel or plate 10, I have connected a strap or wire, 20, with the rod n and the bed 26; or it might be the floor. The sole, held as described in the line of the channel, may be pressed very closely against the welt and upper, between it and the last, so that as the operator forces the awl through the welt and sole neither of the two latter can move, but both will be held forced together very closely, much more closely than is possible in hand-work with 90 the most skilled or best workman. After having taken several stitches, the workman will put his foot on the treadle o' and relieve the pressure of the sole-presser in the channel sufficiently to release the pressure of the 100 same on the shoe to permit the head and shoe to be moved, and the sole-presser to be placed in another part of the channel, as may be necessary. The pressure exerted upon the 105 welt and outer sole near the stitching-point will be such as to bend the sole and welt slightly toward the vamp while the awl is being used and the stitch is being drawn taut, as the edge of the sole, when the latter is rounded and finished after stitching, will occupy substantially such position, this provision enabling 110 the line of stitching in the finished shoe and the welt at the point where the stitches pass through it to be close to the vamp. The pivot 19 permits the sole-presser to be moved laterally to keep its lip in the channel as the shoe or boot is rotated or vibrated. The nut b^5 is notched, so that it is locked by the lever c , as in Fig. 2, when the foot is removed from the treadle c^5 .

I claim—

1. In a hand stitching-jack, a rotating head to hold the upper and sole, combined with the sole-presser to enter the channel in the outer sole, substantially as described.

2. In a hand stitching-jack, a rotating and vibrating head and sole-presser to bear against the outer sole, combined with means, substantially as described, to force the head and sole-presser toward each other to clamp the sole and welt closely together at the point where the holes are opened for the reception of the thread, substantially as described.

3. In a hand stitching-jack, the rotating

120

125

130

head to hold the last, with the upper and sole thereon, combined with the sole-presser, and means substantially as described, to support the same, whereby its position may be changed with relation to the axis of rotation of the head to enable the said presser to bear upon the sole near its edge as the last and shoe are rotated, as set forth.

4. In a hand stitching-jack, the rotating and vibrating jack, and the loosely-pivoted sole-presser, combined with the slide-rod, a spring to move it in one direction, and means, substantially as described, to move it in the opposite direction to enable the said presser 15 to be held in the channel of the outer sole or to be removed therefrom, substantially as described.

5. In a hand stitching-jack, the spindle *b*, its spring, the head pivoted upon the said spindle and adapted to hold the last with upper and soles thereon, and means, substantially as described, to move the said spindle longitudinally, combined with the slide-rod, the movable sole-presser supported thereon, and with means to move the said slide-rod, as and 20 for the purposes set forth.

In testimony whereof I have signed my name to this specification in the presence of two subscribing witnesses.

JOSHUA F. AMES.
